UNITED STATES PATENT OFFICE.

JOEL W. JOHNSON AND ALBERT J. CARPENTER, OF PINE BLUFF, ARKANSAS.

FAUCET.

1,351,657.

Specification of Letters Patent. Patented Aug. 31, 1920.

Application filed August 30, 1918. Serial No. 252,091.

To all whom it may concern:

Be it known that we, JOEL W. JOHNSON and ALBERT J. CARPENTER, citizens of the United States, residing at Pine Bluff, in the 5 county of Jefferson and State of Arkansas, have invented new and useful Improvements in Faucets, of which the following is a specification.

This invention relates to new and useful 10 improvements in faucets and the principal object of the invention is to provide locking means for the faucet to prevent the same from being opened by an unauthorized person.

Another object of the invention is to provide means whereby the parts will be automatically locked when the faucet is closed and also to provide a key for actuating the lock with means for preventing 20 the insertion of the key when the faucet is open.

Another object of the invention is to provide a device of this character which is simple and durable in construction, reliable 25 and efficient in operation and one which can be manufactured and placed upon the market at a minimum cost.

The invention also consists in certain other features of construction and in the 30 combination and arrangement of the several parts, to be hereinafter fully described, illustrated in the accompanying drawings and specifically pointed out in the appended claims.

35 In describing our invention in detail, reference will be had to the accompanying drawings wherein like characters denote like or corresponding parts throughout the several views, and in which:—

40 Figure 1 is a side view of the invention.
Fig. 2 is an end view.

Fig. 3 is a longitudinal section.

Fig. 4 is a view of the valve plate.

Fig. 5 is a section on line 5—5 of Fig. 3.

45 In these views 1 indicates the body of the faucet provided with the outlet spout 2 and an inlet 3. The interior of the body is provided with a cross partition 4 provided with an outlet hole 5 and with a lock receiving 50 chamber 6. 7 is a valve plate provided with a plurality of openings 7', adapted to coincide with the outlet opening 5 when said valve is in open position. This plate is also provided with a square central hole 7". 55 This valve plate rests against the outer side of the cross partition 4. 8 is the stem of

the valve having its outer end of cylindrical shape and seated in the chamber 6. This part of the stem is hollow to receive the locking means. The inner end of the stem 60 is of less diameter and extends through a reduced part of the chamber 6. This inner end of the stem is provided with a square part 9 which fits in the square recess 7" in the valve plate and said square part has 65 a screw threaded extension 10 for receiving a nut 11 which secures the valve plate on said stem. The reduced part of the chamber receives suitable packing material 12 which is covered by a flat ring 13 and a coiled 70 spring 14 surrounding the reduced part of the stem engages with said plate for holding the valve plate tightly against the partition.

A shaft 15 has its end screw threaded into the reduced part of the stem with its outer 75 end extending into the bore of the enlarged part of said stem. This shaft receives a toothed wheel 16 which has its outer end provided with key engaging slots 17. 18 represents a pair of lock bolts having teeth on 80 their inner ends which engage the teeth on the wheel 16. These bolts are placed on opposite sides of the wheel so that both will be retracted on the rotation of said wheel. The bolts are normally held in extended position by springs 19. The ends of the bolts pass through suitable openings in the stem 8. 20 indicates bolt receiving openings diametrically arranged in the wall of the chamber 6. These openings are so arranged 90 that the springs will force the bolts into them when the faucet is closed. The stem of the faucet is provided with a suitable handle 21. 22 indicates a key suitably shaped to engage the wheel 16 for withdrawing the bolts. This key may be provided with any suitable means, such as the barrel 16', for preventing its insertion into the lock when the faucet is open. Such means will also prevent the use of a key not intended to 100 be used with the lock. We cover the end of the lock by a lid 23, suitably hinged to the end of the faucet and adapted to be closed by a set screw 24.

We prefer to make the end 3 detachable so 105 that the valve plate may be removed and inserted in this end. It will be seen that the parts of the lock cannot be tampered with nor removed from the faucet without first detaching the faucet from the pipe and removing the nut 11.

As before stated the springs will force the

locking bolts into their recesses as soon as the handle of the faucet is moved to closed position so that the faucet cannot be opened without the use of the key. When the key is inserted and turned the wheel 16 will be rotated and thus the locking bolts will be withdrawn from the recesses so that the faucet may be opened.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:—

1. A faucet comprising a casing, a valve plate therein, a hollow stem connected with the valve plate, a handle on said stem, locking bolts located in the bottom of the hollow in the stem and adapted to engage a part of

the casing, means carried by said bottom for actuating said bolts the top of the stem being closed and having a key hole therein and a key adapted to pass through said key hole to engage the bolt actuating means.

2. A faucet comprising a casing having a chamber therein having bolt receiving recesses in its walls, a valve plate in said casing, a hollow stem within said chamber having a reduced end engaging the valve plate, a nut for securing said stem to said valve plate, spring means engaging part of said stem for holding the valve plate to its seat, a handle on said stem, a toothed wheel journaled in said stem, locking bolts in said stem having toothed portions engaging the teeth of the wheel, spring means for normally holding the bolts in said recesses and a key engaging the wheel for retracting the bolts.

JOEL W. JOHNSON.

ALBERT J. CARPENTER.
